The ornamental design for a beverage shaker, as shown and described.

DESCRIPTION

FIG. 1 is a top plan view of a beverage shaker showing our new design;

FIG. 2 is a front elevational view thereof; the rear elevational, right side elevational and left side elevational views being identical;

FIG. 3 is a bottom plan view thereof;

FIG. 4 is a partial cross-sectional view taken along line 4-4 of FIG. 1 with the body and base portions of the beverage shaker removed for ease of illustration; and,

FIG. 5 is a partial cross-sectional view taken along line 5-5 of FIG. 3 with the lid and body portions of the beverage shaker removed for ease of illustration.

The beverage shaker is used to contain a beverage, which can then be shaken while contained therein.
